CLAIM

We claim the ornamental design for a hunting ladder, as shown and described.

DESCRIPTION

FIG. 1 is a perspective view of a hunting ladder showing our new design. The broken lines are for illustrative purposes only, and form no part of the claimed design.

FIG. 2 is a front elevational view thereof;

FIG. 3 is a left side elevational view thereof;

FIG. 4 is a right side elevational view thereof;

FIG. 5 is a rear elevational view thereof;

FIG. 6 is a top plan view thereof;

FIG. 7 is a bottom plan view thereof; and,

FIG. 8 is an enlarged perspective view of one of the brace members.
